DESIGN FOR A COMBINED PEDESTAL AND MIRROR

Gus R. Fitzgerald, Ponca City, Okla.

Application February 16, 1948, Serial No. 144,517

Term of patent 14 years

(Cl. D33—9)

To all whom it may concern:

Be it known that I, Gus R. Fitzgerald, a citizen of the United States of America, residing at Ponca City, in the county of Kay and State of Oklahoma, have invented a new, original, and ornamental Design for a Combined Pedestal and Mirror, of which the following is a specification, reference being had to the accompanying drawing, forming a part thereof, wherein:

Figure 1 is a front elevation of a combined pedestal and mirror, showing my new design,

Figure 2 is a side elevation,

Figure 3 is a rear view with the lower portion of the pedestal and base omitted for convenience of illustration, and

Figure 4 is a top plan view.

I claim:

The ornamental design for a combined pedestal and mirror, as shown.

GUS R. FITZGERALD.
